Primary Examiner — Derrick E Holland*Assistant Examiner* — Jennifer O King(74) *Attorney, Agent, or Firm* — Marshall, Gerstein & Borun LLP(57) **CLAIM**

The ornamental design for an outlet plate, as shown and described.

DESCRIPTION

FIG. 1 is a perspective view showing a new design for an outlet plate;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The dashed lines showing portions of the outlet plate are included for the purpose of illustrating environment and form no part of the claimed design.
